UNITED STATES PATENT OFFICE

LOUIS H. WELLENSIEK, OF HOUSTON, TEXAS, ASSIGNOR TO HUGHES TOOL COMPANY,
OF HOUSTON, TEXAS, A CORPORATION OF TEXAS

CORE CATCHER

Application filed January 10, 1929. Serial No. 331,526.

My invention relates to core catchers for use in core drills employed in deep well drilling. It is designed for engaging the core to break it off and withdraw it from the hole when the drill is withdrawn.

The core catchers heretofore employed for the purpose stated are adapted to engage the core by the relative upward movement of the head of the drill, and means are employed to project into contact with the core to grip the same when the drill is raised. This type of device is objectionable as the core engaging members tend to wear and break the core as the drill operates and also they sometimes become broken or clogged and fail to properly function.

It is an object of my invention to provide a core catcher which is entirely out of the path of the core, so as to leave a free and unobstructed passage for the core into the core barrel.

Another object is to provide a core catcher which is moved automatically into engagement with the core before the drill itself is raised.

I desire to employ the weight of the drill and the force of the flushing fluid to actuate the catcher so as to grip the core firmly when the drill is to be removed.

In the drawings herewith, is illustrated a preferred embodiment of the device. Fig. 1 shows a central vertical section through a drill employing my invention, said drill being shown in relation to the core to be engaged.

Fig. 2 is a similar view showing the parts in core engaging position.

Fig. 3 is a transverse section on the plane 3-3 of Fig. 2.

Fig. 4 is a similar section on the plane 4-4 of Fig. 2.

Fig. 5 is a broken enlarged detail in section through one of the gripping dogs.

Fig. 6 is a side elevation of the structure shown in Fig. 5.

Fig. 7 is a top plain view of Fig. 5.

Fig. 8 shows a side and front view of the holding block employed to engage and hold the pull rod.

I have shown my invention adapted for

use in combination with a hard formation core drill. The drill comprises a head 1 of tubular form, having rolling cutters 2 at the lower end. This head is threaded internally at its upper end at 4 for engagement with a special "sub" or drill collar 3. The upper end of the head shoulders against the lower end of the collar at 19, and an annular groove 5 in the upper end of the head serves as a chamber with which water passages 6 in the collar connect. The channels 7 in the head discharge fluid from the chamber upon the cutters.

The internal diameter of the drill collar 3 is increased at 8 to receive a core barrel 9 which is screwed into the said collar and projects upwardly into the drill-stem, not shown.

The drill collar is made up of an upper section 10, and lower section 11, the upper section telescoping over the upper end of the lower section. The upper section engages the shoulder 12 of the lower section; and the lower section engages the shoulder 13 on the upper section. Said upper section is threaded at 16 to engage the drill stem and the telescopic joint between the two sections is made fluid tight by means of packing rings 14 on the upper portion of the lower section.

There is a limited amount of vertical movement between the two sections of the collar but they are keyed together to prevent relative rotation. The keys which connect the two parts are shown at 15. For purposes of assembly, the keys are made up of blocks, see Fig. 8, which may be inserted through openings 17 in the side wall of the upper section. The inner section has keyways 18 to receive said keys, said keyways being slightly longer than the keys to allow a limited relative sliding movement indicated at 18 in Fig. 1.

The blocks 15, which form the keys, are welded in position when the sections are assembled together. The inner face of each block has a T-shaped recess or groove 30 to receive the upper end of the pull rod 20 which fits therein.

The said rods 20 extend downwardly from the keys through channels 28 in the lower section and are secured pivotally to the core engaging dogs 21 adjacent the lower end of

the said lower section. Said dogs are flattened, semi-cylindrical discs, mounted in removable blocks 22 and pivoted to oscillate on pins 23 in said blocks. The dogs 21 are 5 curved slightly transversely upon their inner faces 24 as seen in Fig. 7. Their rear faces are slotted at 25 to receive the lower ends of said rods 20. A pin transversely of each slot 25 has a threaded opening therein to engage 10 the lower end of said rod, as shown in Figs. 5 and 6.

The blocks 22 are shown as separate parts fitted through openings in the side walls of the collar and welded in position. This is 15 for purposes of assembly. The passages 28 are larger than said rods 20, so that said rods can have radial play as the dogs are rotated. There are three sets of core-engaging dogs and rods shown, but any desired number may 20 be employed.

In use, the drill and collar are assembled as shown and inserted into the well for operation. The weight of the drill head and lower section of the collar 3 will cause the 25 lower section to drop relative to the upper section and the dogs 21 will be rotated into core engaging position as shown in Fig. 2. When the bottom of the hole is reached, the weight of the upper section and drill stem 30 will force the two sections of the collar together for drilling, as seen in Fig. 1. As the drill is operated, the core will move upwardly into the collar and core barrel and the dogs 21 will not interfere with its free 35 entrance to the core barrel 9. The dogs fill the recess in which they are housed and no chips nor fragments of material can get behind them.

When it is desired to raise the core drill 40 and core from the hole, the drill stem is drawn upwardly, and the pumps will be kept operating, as the first upward lift is given to the drill. The weight of the drill and lower section of the collar, together with the force 45 of the flushing fluid against the head will tend to hold the drill from rising as the upper section of the collar is lifted to pull upon said rods and rotate the dogs 21 into core-engaging 50 position before the drill is raised. When the keys 15 are at the lower ends of the keyways, the drill will then also be raised together with the core gripped by the dogs 21, as shown in Fig. 2.

The core catcher thus formed is particularly effective in that it does not interfere 55 with the passage of the core upwardly into the core barrel. The dogs are not exposed to wear or breakage, and they are positively moved into core engaging position when the drill-stem is elevated. The core will not be 60 damaged and broken by the dogs as it is being formed, and it will be gripped and withdrawn without failure of the core gripping means.

What I claim as new is:

1. A core drill having a head and cutters thereon in combination with a drill collar, including upper and lower sections telescopically engaged, means to prevent relative rotation of the said sections, core engaging dogs mounted on a horizontal axis in one of said sections and adapted to move in a vertical plane and means on the other section slideable in the first of said sections and responsive to relative longitudinal movement of the sections to move said dogs positively to or from core engaging position. 70

2. A core drill having a head and cutters thereon in combination with a drill collar, including upper and lower sections telescopically engaged, keys in one of said sections engaging within keyways in the other section to prevent relative rotation thereof, core engaging dogs mounted on a horizontal axis 80 in one of said sections and adapted to move in a vertical plane and means responsive to relative longitudinal movement of the sections to move said dogs both to or from core engaging position. 85

3. In a core drill, a drill collar having upper and lower sections, a core barrel therein, core-engaging means below said core barrel, and rigid means on said upper section connected directly with said core-engaging 90 means actuated by the relative longitudinal movement of said sections to force said core engaging means positively into core engaging position.

4. In a core drill, a drill collar, having 100 upper and lower sections, means securing said sections together but allowing a limited vertical relative movement of said sections, a core barrel therein, core-engaging means below said core barrel, and means actuated by 105 the weight of the drill and the pressure of flushing fluid to move the lower section relative to the other, when said drill collar is raised, and force said core engaging means into contact with the core. 110

5. In a core drill including a tubular head and cutters thereon, a drill collar having upper and lower sections which have a limited vertical movement relative to each other, and core engaging dogs normally retracted 115 within the walls of said drill collar and means including rigid rods actuated by the relative upward movement of said upper section to positively move said dogs to engage a core. 118

6. A core drill, a drill collar thereon, a core barrel in said collar, there being a free and unobstructed passage from said drill to said core barrel, core engaging dogs housed within said drill collar and pivoted on a horizontal axis to be partially rotated to project into said passage by an upward pull on said drill collar. 125

7. A core drill, a drill collar comprising upper and lower relatively movable parts, 130

5 a set of core engaging dogs housed in said lower section, said dogs being pivoted in said section to swing into engagement with the core, and rods connecting said dogs with said upper section of said drill collar whereby said dogs may be moved to core engaging position.

10 8. A core drill, a core barrel, there being an unobstructed passage from said core drill into said core barrel, a telescopic joint above said drill, core-engaging devices normally housed in the wall of said passage, and means including rods connecting said devices with the upper portion of said joint actuated by 15 relative movement of the parts of said joint to actuate said devices to engage the core.

20 9. A core drill, a core barrel above said drill, a tubular drill collar on said drill, comprising upper and lower sections telescopically engaged to allow a limited relative longitudinal movement, core engaging dogs normally housed wholly within the walls of said lower section, and rods connecting said dogs with said upper section, 25 whereby said dogs may be moved to engage a core.

25 10. A core drill, a core barrel above said drill, a tubular drill collar on said drill, comprising upper and lower sections telescopically engaged to allow a limited relative longitudinal movement, core engaging dogs normally housed wholly within the walls of said lower section, said dogs being fixed against sliding movement in said section, and rods connecting said dogs with said upper section, whereby said dogs may be moved to engage a core.

30 11. In a core drill, a drill collar, a core barrel, core engaging means below said core barrel in said collar, and means actuated by the weight of the drill and core barrel to force said core engaging means into contact with the core.

35 12. In a core drill, a drill head, a drill collar thereon, said collar being formed in upper and lower sections telescopically connected to allow a limited relative longitudinal movement of said sections, dogs pivotally supported in said lower section, rods thereon connecting said dogs with said upper section whereby said dogs are positively rotated by the relative longitudinal movement of said sections.

40 13. In a core drill, a drill head, a drill collar thereon, said collar being formed in upper and lower sections telescopically connected to allow a limited relative longitudinal movement of said sections, dogs pivotally supported in one of said sections, rods on 45 said dogs connected with the other of said sections and adapted to move said dogs by the relative longitudinal movement of said sections.

45 14. In a core drill, means whereby said drill may be rotated, a telescopic joint in

said rotating means, including upper and lower members, a set of core-engaging jaws on one of said members, rigid operating devices pivotally connected with said jaws at one end and with the other of said members at the other end, and means to limit the relative movement of said members.

In testimony whereof I hereunto affix my signature this 7th day of January A. D. 1929.
